UNITED STATES PATENT OFFICE.

EDWARD P. SHURICK, OF KNOXVILLE, TENNESSEE.

COMBINED LETTER AND ENVELOPE STUFFER OR THE LIKE.

1,417,211.

Specification of Letters Patent. Patented May 23, 1922.

Application filed December 14, 1921. Serial No. 522,240.

To all whom it may concern:

Be it known that I, EDWARD P. SHURICK, a citizen of the United States, residing at Knoxville, in the county of Knox, State of Tennessee, have invented certain new and useful Improvements in Combined Letter and Envelope Stuffers or the like, of which the following is a description, reference being had to the accompanying drawing and 10 to the figures of reference marked thereon.

This invention relates to mailing devices, and more particularly to a combined letter and broadside or the like adapted to be inserted in an envelope to be mailed.

15 Heretofore, in direct-by-mail advertising, whenever it has been desirable to send out a sales letter or the like with a descriptive pamphlet, leaflet, folder or envelope stuffer, it has been necessary to enclose the pamphlet, leaflet or the like, in with the letter loosely. Due to the fact that the letter and the enclosure were on separate sheets of paper, many times the enclosure would be left in the envelope, be lost, or be destroyed. 20 To prevent this, it has generally been the practice to clip the enclosure to the letter by means of a clip or fastener.

The present invention has for its principal object the elimination of all these difficulties by providing a letter sheet adapted 30 for general correspondence, in which the letter is provided with an integral extension adapted to fold on the edge line of and into the limits of the letter sheet to provide 35 a distinct folder, leaflet or the like composed of one or more folds adapted for any necessary use, such as a price list, advertising matter, a sample holder, a check, draft or the like, and such folder being also capable 40 of carrying and enclosing additional sheets or samples or the like.

Still another object of this invention is to provide a device of the character described in which the letter sheet is provided 45 with a distinctive portion segregated from the writing field of the letter sheet and adapted for the purpose desired, said distinctive portion having an integral extension adapted to form a desired number of 50 folds and foldable on the edge line of and into the limits of the distinctive portion to provide a folder or the like for the purpose desired.

Another object of this invention resides 55 in providing a letter sheet with a distinctively colored portion segregated from the

writing field of the letter sheet and provided with an integral extension also similarly distinctively colored and foldable along the edge of the letter sheet into the 60 limits of the segregated portion to provide a folder adapted to receive printed matter, samples and the like.

These and other objects will in part be obvious and will in part be hereinafter more 65 fully disclosed.

In the accompanying drawings:—

Figure 1 is a view of the letter sheet with the extension folded within the letter sheet;

Fig. 2 is a similar view with the extension opened; and

Fig. 3 is a view of the folder provided with additional leaves.

Fig. 4 is a specific form of Fig. 1.

The invention combines two separate 75 forms now in general use, namely a letter sheet and an envelope stuffer, broadside, price list, booklet, pamphlet, or leaflet or the like. In the drawings the former is shown as a letter sheet 1, provided with the 80 usual heading 2, and the blank field 3 adapted for general correspondence, such as a typewritten, mimeographed, or multi-graphed letter. The letter sheet is also formed with a distinctive portion 4 segregated from the writing field 3 of the letter. 85 This appearance of segregation may be accentuated in any desired manner, as by a blank border line 5, or by appropriately ruled lines 6, or by giving the distinctive 90 portion a separate color or tint, as is preferred. This portion 4 is of desired size, preferably of size and shape to correspond with the interior fold-lines or creases X, Y, or Z on which the letter sheet is folded in 95 order to properly insert it in an envelope as customary. In this manner, the distinctive portion will not be bent or become rumpled.

Obviously such distinctive portion may be located at other desired portions of the 100 letter sheet, such as on the bottom, top, or opposite side, and there may be more than one, if desired. In certain aspects of the invention it is desirable to form this distinctive portion 4 of a particular shape of 105 any commodity to be advertised, such, for instance, a bottle displaying a brand of medicine, a phonograph, a popular brand of a can of soup, or a lock. For instance, in Fig. 4, the letter sheet 1' has the distinctive portion 4' which is provided with an extension 7', distinctive in contour and ap-

pearance and resembling a bottle of medicine.

This distinctive portion 4 of the letter sheet 1 is provided with an integral extension 7 which may be of such dimensions as to form a single additional foldable portion corresponding, if desired, in size, shape and general distinctive appearance to the portion 4 or it may consist of a plurality of folds 10 of desired size and shape. In the preferred form, the extension 7 is shown as a single leaf 8 adapted to receive any desired printed matter or the like on one or both sides; such, for instance, as the price list or catalog 15 log illustrated. This extension folds on line 9 which is a continuation or extension of the border or edge line of the letter sheet. By this fold, the extension can be turned or folded back into the limits of the letter 20 sheet and since the fold 8 is of the same size and shape as the portion 4, it will fold onto this portion 4 and form a cover for it, as shown in Fig. 1. The obverse face of this extension 7 shown in Fig. 1 is provided 25 generally with any appropriate folder or leaflet heading or facing. While the reverse face thereof shown in Fig. 2 is provided with desired printed or written matter or other data and information.

30 While in the present instance this extension is shown as carrying printed matter in the form of a price list or catalog, it is within the contemplation of this invention to form this extension as a check, draft, or 35 the like, in which case it is desirable to form the line 9 as a perforated line to permit easy detachment of the same. In certain other cases, the letter sheet may take the form of an invoice or statement, and the foldable 40 extension may be utilized for advertising purposes as before described. So also where the distinctive portion 4 is of particular shape, as for instance, a bottle of medicine, phonograph, can of soup, or a lock, the extension 8 is made of size, shape and appearance 45 to correspond. The obverse and reverse faces of the extension of such outline being used for advertising or the like.

In certain other instances, it is highly desirable 50 to form the folder with an interior leaf or plurality of leaves attached in any desirable manner, as by sticking or fastening with staples or the like. Such a form is shown in Fig. 3, wherein the extra double 55 fold 10 is fastened to the distinctive portion preferably at the crease line 9 as by the staples 11. Obviously instead of a double fold there may be a single leaf attached in a preferred manner, and this sheet may contain 60 printed matter or may have pasted or attached thereto samples of various description. The advantages of the form shown in Fig. 3 will be readily appreciated for the reason that in present-day business a large 65 manufacturing firm making ten or twelve

different products has a large general correspondence daily. By means of the form shown in Fig. 3, the firm can turn over to their stenographers during any particular month, letter sheets with an integral envelope stuffer covering one of their products. All general letters written that month would be on that form. In the following month, the envelope stuffer would be changed by attaching a different internal folder 10 to 70 cover some other one of their ten products, and all general letters sent out that month would be on that form. This same idea is applicable to the form shown in Fig. 1, except that the entire letter would have to 75 be reprinted with a corresponding number of different distinctive portions. At present, when firms advertise in this manner, they not only have to pay for an extra envelope stuffer but have to pay an additional amount for its insertion in the envelope. 80

It will be obvious from the above description that the invention has many advantages in that both letter sheet and stuffer, pamphlet or the like may be printed at one time, thus reducing the cost of the two items now printed separately; that the envelope stuffer, pamphlet, folder or leaflet being a part of the letter, statement, invoice or other 95 printed matter cannot be lost or become detached; that it provides an envelope stuffer or the like which is the proper size for a standard file and will be filed with the letter attached in such file; that the advertising 100 value of the printed matter is greatly enhanced owing to the fact that a prospect, when he opens the letter, has before him, at one time, the letter, samples, price list and description so that he can read over the 105 proposition without laying down the letter to pick up the pamphlet or vice versa; that furthermore the general appearance of the letter is made more attractive and interesting by the distinctively colored appearance 110 of the folder, and that by reason of this distinctive appearance the folder appears to be separate from the letter.

It is obvious that the invention is capable of various and sundry modifications and 115 that the scope of the invention is not to be restricted except by the language of the following claims.

Having thus described the invention, what is claimed as new is:—

1. A device of the class described comprising a letter sheet having an integral flap or extension provided with suitable indicia, said flap or extension being of less length than the side of said letter sheet of which 125 it is a part, said flap being foldable on and within the marginal line of the letter sheet in and for the purpose set forth.

2. A device of the class described comprising a letter head having a letter portion and 130

- 5 a segregated portion of distinctive appearance, said segregated portion having an integral extension foldable on and within the marginal line of the letter head and of less length than the marginal line of the letter head on which it folds, said extension having substantially the same distinctive appearance on both sides thereof as said segregated portion.
- 10 3. A device of the class described comprising in one piece, a headed letter sheet adapted for general business correspondence and an envelope stuffer, said envelope stuffer comprising a desirable number of flaps adapted to fold into the body of the letter head thereby simulating a letter head with an apparently separate envelope stuffer attached thereto.
- 15 4. A device of the class described comprising a letter sheet having an integral flap or extension having indicia thereon and adapted to be folded on the border line, and within the limits of the letter sheet, and a desired number of sheets secured to said letter sheet and arranged to form the desired number of inner leaves for said folder.
- 20 5. A device of the class described comprising a letter sheet provided with a heading normally placed thereon and a written message, said letter sheet having an integral flap or extension provided with suitable indicia, said flap or extension being disposed so as to fold on and within the marginal line of the letter sheet and arranged so that when folded it will not cover the letter head- 35
- 25 6. A device of the class described comprising a standard letter head having an integral extension having suitable indicia thereon adapted to fold on and within the marginal line of the letter head so as to simulate a separate attachment, said integral extension being of such dimensions and disposed so as to fold within the standard folded lines or creases when the letter head is folded in the customary manner whereby the extension is not bent in folding the letter. 40
7. A device of the class described comprising a letter sheet having an integral flap or extension shaped to resemble in contour and appearance an article of merchandise to be advertised, said flap or extension being foldable on and within the marginal line of the letter sheet. 45

In testimony whereof, I affix my signature. 55
EDWARD P. SHURICK.
